UNITED STATES PATENT OFFICE.

JOHN S. HEATON, OF PHILADELPHIA, PENNSYLVANIA.

DESIGN FOR A SKIRT-HANGER.

SPECIFICATION forming part of Design No. 29,038, dated July 12, 1898.

Application filed May 11, 1898. Serial No. 680,416. Term of patent 14 years.

all whom it may concern:

Be it known that I, JOHN S. HEATON, a citizen of the United States, residing in Philadelphia, Pennsylvania, have invented a certain new and useful Design for a Skirt-Hanger, which the following is a specification. My design for a skirt-hanger is clearly illustrated in the accompanying drawing, in which the figure represents the skirt-hanger in perspective. The leading feature of the design is the arched frame with a vertically-arranged bar having a series of crimps in it. A is the frame, having an arched section and a cross-bar a' at the base. Extending

from the bottom bar to the highest point of the arch is a bar b , having a series of crimps b' . Forming a continuation of this bar b is a suspension-rod c .

I claim—

The design for a skirt-hanger as herein described and as shown in the accompanying drawing.

In testimony whereof I have signed my name to this specification in the presence of two subscribing witnesses.

JOHN S. HEATON.
